UNITED STATES PATENT OFFICE.

WILLIAM SCHWAGERMANN, OF YONKERS, NEW YORK, ASSIGNOR TO WARD
LEONARD ELECTRIC COMPANY, A CORPORATION OF NEW YORK.

RESISTANCE UNIT.

1,366,600.

Specification of Letters Patent. Patented Jan. 25, 1921.

Application filed June 30, 1919. Serial No. 307,744.

To all whom it may concern:

Be it known that I, WILLIAM SCHWAGERMANN, a citizen of the United States, residing at Yonkers, in the county of Westchester and State of New York, have invented certain new and useful Improvements in Resistance Units, of which the following is a specification.

The main object of my invention is to provide a resistance unit of simple and rugged construction and which may be economically manufactured. Another object is to provide means for readily and firmly mounting the unit endwise upon a support in fixed position. Another object is to adapt the unit to be mounted in a definite relative position to its support and to bring corresponding terminals in proper relative position. Other objects and advantages will be understood from the following description and accompanying drawings showing preferred embodiments of my invention.

Figure 1 is a longitudinal cross section of one form of my invention; Fig. 2 is a lower end view of the body of the unit showing the terminals in their relation thereto; Fig. 3 is a similar upper end view; Fig. 4 is a longitudinal cross section of another form of my invention; and Fig. 5 is a lower end view of the body portion and showing the terminals.

Referring to the particular form shown in Figs. 1 to 3, the body portion of the unit is a tube 10 of earthenware, porcelain or other suitable insulating material. It has two longitudinally extending holes 11 and 12 parallel to each other and independent of each other. The resistance wire 13 is wound around the tube and held in place and protected by an enamel coating 14, or other adhesive insulating and protective coating.

Extending through the hole 11 is conductor or lead 15 shown as a narrow strip of copper or other metal. The upper end of the strip is bent outwardly and flatwise through a notch 16 at the upper top of the tube. A few turns of the wire 13 is wrapped around the end of the strip which end is bent over on itself to firmly clamp the resistance wire and also bent down against the tube. The insulating coating 14 is applied to and embeds the joint between the wire and conducting strip. The strip is shown

twisted 90 degrees in the hole 11 and passes out of its lower end, extends a short distance outwardly in a radial direction through a slot 17 formed in the insulating body and extends downwardly through the outer portion of the slot 17 as shown in Fig. 1. The lower end of the strip forms one terminal of the unit.

The lower end of the tube 10 has an offset portion at one side in which the slot 17 is formed. It also has an offset portion at the opposite side in which a slot 18 is formed. This slot extends parallel to the tube axis and in a radial plane. Another conducting strip 19 extends through the slot and the resistance wire 13 is electrically connected to its upper end by a few turns of the wire being wrapped around it and clamped by the end of the strip being bent over on itself. The end of the strip is also bent down flatwise against the top surface of the offset of the tube 10. It is also covered with and embedded in the insulating coating 14. The lower end of the strip 19 forms the other terminal of the resistance unit. The lower end of the insulating tube has formed in it a circular depression 20 and between the two offsets of the tube is a rectangular opening 21 so that the tube is adapted to be placed on and bridge a supporting bar 22 which may be of metal, and upon which a series of tubes may be mounted in a row. The unit is held in place by a screw 23 passing through the hole 12, the head of the screw engaging the upper end of the tube and seated in a cutaway portion.

In order to further protect the strip 15 in the lower end of the tube and to keep it in place in its slot, cement or plaster of Paris 24 may be forced into the slot 17 and depression 20; also when the supporting rod 22 is of a standard size, a gage the size of the support 22 or a little larger may be forced in between the offsets of the tube after the cement has been applied and before it has set so that the cement is formed around the gage to accurately fit it. The gage is then removed and each unit will thereafter fit a similar bar and insure the units being in alinement on the bar and having a uniform position thereon. In this process of shaping the lower end of the tube to fit a bar the gage may have a pin extending from it to pass into the hole 12 to

keep it from being closed up by the cement, or the hole may be extended through the cement after the gage is removed.

It will be apparent that the conductors 15 and 19 may be readily stamped from sheet metal and bent to the desired form; and in placing the conductor 15 in the tube it may be pushed up through the lower end, after which the upper end is bent over as above described.

The construction shown in Figs. 4 and 5 is the same as that of Figs. 1 to 3, except a modified construction as to housing and form of the lower end of conductor 15. In Figs. 4 and 5 the left-hand offset portion of the body 10 in addition to having the slot 17 for receiving the lower end of the conductor 15', has another slot 25 at right angles to slot 17. The conductor 15' is bent at right angles at the upper corner of the slots 17 and 25 and from that point extends downwardly through the slot 25 as shown in Figs. 4 and 5. The lower part of conductor 15' is thus housed in slot 25 and separated from the support 22 by a wall of insulation 26. With this construction it is unnecessary to add cement or other filling around the lower part of conductor 15'; and the opening between the offset portions of the body 10 may be initially gaged to fit the bar 22.

Although I have shown preferred embodiments of my invention various modifications may be made without departing from the scope thereof.

I claim:—

1. A resistance unit comprising a tube of insulating material having two holes provided therein and lengthwise therethrough adapted to have elements inserted therein, supporting means for the unit passed through one of said holes, and a conducting lead passed through the other of said holes.

2. A resistance unit comprising a tube of insulating material, a resistance on the outer surface of said tube, the tube having two openings therethrough independent of each other adapted to have elements inserted therein, a conducting lead connected to the resistance at one end and passed through one of said openings, and means for supporting the unit passed through the other of said openings.

3. A resistance unit comprising an insulating body having three longitudinal openings therethrough and adapted to have elements inserted therein, a resistance on the outside of said insulating body, two conducting leads connected to said resistance and passed through two of said openings respectively, and supporting means for the unit passed through the third opening.

4. A resistance unit comprising an insulating body having a longitudinal opening and having offset portions at one end and having openings in said portions, said openings be-

ing adapted to have elements inserted therein, a resistance on the outside of said insulating body, a conducting lead connected to said resistance and passed through said longitudinal opening and through an opening in one of said offset portions, and a conducting lead also connected to the said resistance and passed through an opening in another of said offset portions.

5. A resistance unit comprising an insulating body having an opening at one end for receiving and bridging a support and having a longitudinal opening adapted to have an element inserted therein, a resistance on said insulating body, terminals connected thereto, and means passed through said longitudinal opening for securing the unit to the support.

6. A resistance unit comprising an insulating body having a pair of openings at one end of said body, a resistance on the outside of said body, and a pair of leads connected to said resistance and extending through said openings respectively at the end of said body.

7. A resistance unit comprising an insulating body having two slots at one end of said body, a resistance on the outside of said body, and two leads in the form of strips connected to said resistance and housed in and extending through said slots respectively.

8. A resistance unit comprising an insulating body having a longitudinal opening therethrough and slotted openings at one end, a resistance on the outside of said body, and two leads in the form of strips connected to said resistance and housed in and extending through said slots respectively, one of said leads also extending through said longitudinal opening.

9. A resistance unit comprising an insulating body having two longitudinal openings and having slotted openings at one end adapted to have elements inserted therein, a resistance on the outside of said body, two leads in the form of strips connected to said resistance and housed in and passed through said slots respectively, one of said leads also passed through one of said longitudinal openings, and supporting means for the unit passed through the other of said longitudinal openings.

10. A resistance unit comprising an insulating tube having two longitudinal openings and two offset portions at one end and having slots in said offset portions respectively, two leads in the form of strips connected to said resistance and housed in and extending through said slots respectively, one of said leads also extending through one of said longitudinal openings and supporting means for the unit extending through the other of said longitudinal openings.

11. A resistance unit comprising an insulating body having an offset open slotted end portion, a resistance on the outside of said body, and conducting leads connected to said resistance, one of said leads being housed in said offset slotted end portion. 5
12. A resistance unit comprising an insulating body having an offset open slotted end portion, a resistance on the outside of 10 said body, conducting leads connected to said resistance, one of said leads being housed in said offset slotted end portion, and a filling of insulating material for retaining said lead in said slotted end portion. 15
13. A resistance unit comprising an insulating body having a longitudinal opening therethrough and having an offset open slotted end portion, a resistance on the outside of said body, and conducting leads connected to said resistance, one of said leads passed through said longitudinal opening and housed in said offset slotted end portion. 20
14. A resistance unit comprising an insulating body having a longitudinal opening therethrough and having an offset open slotted end portion, a resistance on the out- 25
- side of said body, conducting leads connected to said resistance, one of said leads passed through said longitudinal opening and housed in said offset slotted end portion, 30 and a filling of insulating material for retaining said lead in said slotted end portion. 35
15. A resistance unit comprising an insulating body having a slotted end portion, said slotted end portion having parts of the slot at right angles to each other, a resistance on the outside of said body, and conducting leads connected to said resistance, one of said leads being housed in said slotted end portion. 40
16. A resistance unit comprising an insulating body having a longitudinal opening therethrough and having a slotted end portion, said slotted end portion having parts of the slot at right angles to each other, a 45 resistance on the outside of said body, and conducting leads connected to said resistance, one of said leads passed through said longitudinal opening and being housed in said slotted end portion.

WILLIAM SCHWAGERMANN.
